YORK.

ELECTRICAL APPARATUS.

1,340,588.

Specification of Letters Patent. Patented May 18, 1920.

Application filed April 29, 1915. Serial No. 24,791.

To all whom it may concern:

Be it known that I, JULIUS B. WANTZ, a citizen of the United States, residing at Chicago, in the county of Cook and State of Illinois, have invented a new and useful Improvement in Electrical Apparatus, of which the following is a specification.

My invention relates to novel and improved features of electrical apparatus devised more particularly for use in X-ray work, as hereinafter set forth.

Certain of my objects are to provide for the accurate regulation of the current supplied to the X-ray tube; to provide for the adequate control of the electrical device controlling the amount of current supplied for X-ray purposes, from any one of a plurality of locations, as for example, from a plurality of rooms, in each of which an X-ray tube or tubes is, or are, located and a single transforming device is employed; to provide in a system of the character just stated, namely, one involving a single transforming device for supplying current to either one or the other of two tubes located in two different rooms, and wherein the wires are disposed preferably in the upper part of the rooms, and where the X-ray tubes employed are of a character involving heating elements, as in the case of the so-called "Coolidge" tubes, switch mechanism adapted to direct both the high tension and low tension current to either of the tubes; and other objects as will be manifest from the following description.

Referring to the accompanying drawings,—

Figure 1 is a view in the nature of a diagram of a system embodying my invention, this view illustrating the two rooms with an X-ray tube of the Coolidge type in each, together with an overhead system of wiring, and adapted to be supplied by a single transforming device, with a switch for controlling the supply of high tension and low tension current to either of said tubes, and with a choke-coil controlling the current supplied by the transformer, with means for operating the choke-coil from either of the rooms. Fig. 2 is a view in vertical longitudinal sectional elevation of the shiftable member of the switch device shown in Fig. 1 for switching the current from one tube to the other; and Fig. 3, a view in front elevation, partly broken away, showing the

preferred form of device employed for regulating the supplying of heating current to the tubes.

In the particular arrangement shown the apparatus is designed for use where X-ray tubes are located in different rooms and where it is desired that a single transformer apparatus be employed, this arrangement shown involving in part what is termed overhead wiring, or in other words, the location of certain of the current conducting wires near the ceiling of the rooms. The apparatus as shown is intended for use with X-ray tubes of the so-called Coolidge type above referred to, these tubes being represented at 18 and equipped with binding posts 17 and 20, the binding post 17 connecting with one of the terminals of the heating-element-equipped electrode of the tube and the other terminal of this electrode being connected with the binding post 20.

The opposite walls of two adjacent rooms are represented at 82, and a partition separating these rooms, at 83. This installation involves wires 84 and 85 in one room, each secured at one end to an anchorage 86 carried by an insulator 87 and near their opposite ends connected with terminals 88 fastened to a switch device, the frame of which is represented at 99, with a meter 89 supported from the wall and electrically interposed in the wire 84, the wire 84 being connected with the ends of a block 90 of insulating material, whereby the wire 84 may be maintained in taut condition. A third, overhead, wire 91 is connected at one end with an insulated anchorage 92 and at its opposite end with a terminal 93 of the switch device, this wire having interposed therein a meter 94, supported from the wall, with a block 95 of insulating material, like the block 90, to which the wire 91 is secured, as and for the purpose explained in connection with the wire 84. All three of the wires 84, 85 and 91 pass through an insulator 95^a, composed of a sheet of glass set in the partition 83. The overhead wiring in the room on the opposite side of the partition 83 is the same as the wiring just described, the three wires corresponding to the wires 84, 85 and 91, these wires, with the apparatus connected therewith, as described of the wires in the room at the lefthand side of the partition 83, being given the

same designations as the latter. The tubes 18 are connected at the ends thereof opposite to those equipped with the heating elements, with the wires 91, by means of the wires 96, and the two terminals 17 and 20 are connected, respectively, with the wires 84, and the wires 85, by wires 97 and 98.

The wires 84, 85 and 91 are connected with a switch construction involving my improvement, for supplying high tension and low-tension current to either set of wires 84, 85 and 91, as desired. The switch device comprises a frame 99 which would be supported in any suitable manner from the wall of ceiling of one of the rooms to extend preferably in a horizontal plane. The frame 99 is provided at its opposite ends with sets of contacts of three each, the contacts at the lefthand side of the switch device being represented at 100, 101, and 102, and connected, respectively, with the wires 84, 85 and 91 in the room at the lefthand side of Fig. 1 by means of the terminals 88 and 93; and the contacts at the right-hand side of said device being represented at 103, 104 and 105, and connected respectively with the wires 84, 85 and 91, strung overhead in the room at the righthand side of Fig. 1 by means of the terminals 88 and 93. The contacts 100, 101, 103 and 104 are preferably of the common variety, each involving two spring-arms spaced apart, and the contacts 102 and 105 are preferably in the form of pins secured in lugs 106 on the frame 99. Extending transversely of the frame and located within it is a rocker member 107 connected at its opposite ends with metallic stub-shafts 108 and 109, which are journaled in opposite sides of the frame 99 to extend beyond the outer faces thereof, as represented in Fig. 2, whereby the member 107 is provided journal support on the frame 99. A section 110 of metal rod is located in the interior of the member 107 in line with the stub-shaft 109 and insulated therefrom by a block 111 of insulating material, a screw 112 passing through and interlocking with a metallic strip 113, which almost completely surrounds the member 107, electrically connecting this strip with the bar section 110. The member 107 is provided with three contact arms 114, 115 and 116 which are screwed into and thus make electrical contact with, the members 109, 110 and 108 respectively. The arms 114, 115 and 116 are so positioned on the member 107 that these arms will enter between the parts of the contacts 100 and 101 and engage the contact pin 102 when the shaft 107 is rotated counter-clockwise in Fig. 1, and will electrically contact with the contacts 103, 104 and 105 when the shaft 107 is turned in the opposite direction.

A spring-finger 117 secured to a metal clip 118, fastened to the frame 99 and having a ring 119 for connection with a terminal,

yieldingly bears against the strip 113 regardless of the movement of the shaft 107; a spring-finger 120 connected with a metal strip 121 and having an eye 122 for connection with a terminal, yieldingly bears at all times against the outer end of the shaft 109; and a spring-finger 123 supported on a depending extension 124 on the frame encircles the outer end of the shaft 108 and yieldingly bears at all times against a metal enlargement 125 thereon. The wires which would lead from any suitable source of high tension current for energizing the X-ray tubes, are represented at 15 and 15^a, the wire 15 connecting with the spring-finger 123 and thus in electrical contact with the arm 116, and the wire 15^a connecting with the eye 122 and thus in electrical connection with the arm 114. The wires for conducting the current to the heating elements of the tubes 18 for energizing these elements, are represented at 23 and 24, these wires being connected respectively with the eyes 119 and 122, and thus in electrical connection with the arms 115 and 114, respectively. In the arrangement illustrated, the wires 23 and 24 lead from a transformer 25 supplied with current through wires 26 and 27 and 27^a, the wires 26 and 27 leading from any suitable source of current supply, and the wires 27 and 27^a being connected with means, under the control of the operator, for regulating the amount of current delivered from the transformer to the heating elements of the tubes, the form of regulator for this purpose being a choke-coil, represented at 75, interposed in the wire 27.

The construction of the choke-coil which I prefer to employ is the one illustrated in the drawings and employs a plate 76 which is adapted to be secured to the partition 83 and supporting thereon the coil 36, surrounding one end of a tube 35. The tube 35 contains a core 40 of magnetic material, preferably laminated iron, the strips forming this core being secured in any suitable manner to a bar 41 provided centrally of this core and extending beyond the latter at its opposite ends. The tube 35 carries a stop device 52, which projects into the interior of the tube and serves to prevent accidental withdrawal of the core 40 from the upper end of the tube 35 and being preferably adjustable longitudinally of the tube 35 for preventing current, beyond a certain strength, from passing to the heating elements of the tubes 18. The choke-coil is also provided with automatically operating switch mechanism for breaking the circuit when the core 40 is moved to innermost position and automatically reestablishing the circuit upon withdrawing the core, these means comprising a contact finger 64, which is pivotally mounted on the base 76 and is adapted to be moved 130

from one to the other of contacts 71 and 72 on said base, this contact member extending into the path of movement of the rod 41, in moving to lowermost position in the tube 35. 5 A spring 69 operates to raise the contact member 64 out of engagement with the contact 72, when the core 40 is raised. The wire 27 connects through the binding post 60 with one terminal 36^a of the coil 36, and the wire 10 27^a connects through the post 61 with the contact 71, the contact finger 64 being electrically connected, at its pivot, with the other terminal 36^b of the coil 36. From the foregoing it will be understood that when the 15 core 40 is in lowermost position, the contact finger 64 will be depressed out of engagement with the contact 71 and thus no current will traverse the coil 36, but upon raising the core 40, the finger 64 will immediately rise, engaging the contact 71 and closing the circuit through the coil 36.

In the particular arrangement illustrated cables 126 and 127, extending over pulleys 128, 129, 130 and 131 in the two 20 rooms, connect in a manner, not shown, with the upper end of the bar 41, the opposite ends of these cables in the two rooms being provided with counterweights 132 and 133. The counterweights are of such weight 25 that together they will substantially balance the weight of the movable portions of the choke-coil device with which the cables 126 and 127 are connected, so that the operator, operating in either room, may, by raising 30 or lowering the counterweight in the room, adjust the core 40 relative to the coil 36, the core thiereupon remaining in the adjusted position, it being understood that when either of the counterweights 132 or 133 is 35 raised or lowered the other of these counterweights will rise or descend as the case may be, in unison therewith.

The shaft 108 is provided with any suitable mechanism for rocking it from a position in which the arms 114, 115 and 116 engage with the contacts at one end of the frame 99, to a position in which these arms engage with the contacts at the other end of the frame, or to an intermediate position, 45 the mechanism shown for this purpose comprising a cross-arm 134, to the opposite ends of which the ends of a cord 135 are connected, the loop of this cord extending into such position that it will be convenient of 50 operation by the operator.

It will be understood from the foregoing that by the arrangement shown in the drawings both the high and low tension current supplied to the switch device, may be directed to either of the tubes 18 as desired, 55 by shifting the rotatable member 107 as hereinbefore explained, thus supplying either of the tubes 18, at the will of the operator, with X-ray-producing current, and current for exciting the heating element of

the tube, without involving more than one transforming apparatus and current regulating device therefor, the latter being operable from either of the rooms.

The feature of so locating the conductors 70 for the low-tension and the high-tension current that they are remotely disposed relative to the tube, as for example in overhead position, is of advantage as thereby 75 danger to the operator and patient is reduced to the minimum, as accidental contact with the high-tension conductors is avoided, and furthermore the apparatus is more economical of construction.

While I have illustrated and described 80 a particular embodiment of my invention, I do not wish to be understood as intending to limit it thereto, as the same may be variously modified and altered without departing from the spirit of my invention, it being my intention to claim my invention as 85 fully and completely as the prior state of the art will permit.

What I claim as new and desire to secure by Letters Patent is:

1. In X-ray apparatus for X-ray tubes having electrical heating elements, the combination of a plurality of disconnected sets of wires, certain of which are adapted for connection with the heating elements of 95 X-ray tubes of said type, a source of low tension current, means for connecting said source of low tension current with any one of said sets of wires, single means operating when actuated to regulate the flow of 100 low tension current to said wires, and a plurality of independently operative means located at different points and adjacent said tubes, respectively, for actuating said last referred to means to control the low tension current.

2. In a system for energizing X-ray tubes having heating elements, a plurality of said tubes, a source of low potential current, a source of overhead high potential current, 110 two sets of wires of three each, two of the wires of each set adapted for carrying the current from said first-named current-source to said heating elements and one of said two wires of each set and the third wire of each set thereof adapted for carrying the current from said source of high potential current to the anodes and cathodes of the tubes, means for switching the high and low potential current from said sources 115 120 to either of said sets of wires, and single means for varying the low potential current to either set of wires, interposed between said switching means and said source of low potential current.

3. In a system for energizing X-ray tubes having heating elements, a plurality of said tubes, a source of low potential current, a source of high potential current, two sets of overhead wires of three each, two of 130

the wires of each set adapted for carrying the current from said first-named current-source to said heating elements and one of said two wires of each set and the third wire of each set thereof adapted for carrying the current from said source of high potential current to the anodes and cathodes of the tubes, means for switching the high and low potential current from said sources to either of said sets of wires, means operating when actuated to regulate the flow of

low tension current to said wires and a plurality of independently operative means located at different points and adjacent said tubes, respectively, for actuating said last 15 referred to means to control the low tension current.

JULIUS B. WANTZ.

In presence of—

J. THIELEN,
GEORGE M. RENNIE.
